UNITED STATES PATENT OFFICE

FRANK D. JONES, OF OTTUMWA, IOWA, ASSIGNOR TO DAIN MANUFACTURING COMPANY
OF IOWA, OF OTTUMWA, IOWA, A CORPORATION OF IOWA

ALARM DEVICE FOR BALING PRESSES

Application filed November 10, 1930. Serial No. 494,540.

My invention relates to alarm devices for baling presses and operating to indicate to an operator of a press that sufficient material has been fed into the press to form a bale, and the object of my invention is to provide a device of this character, readily mountable upon a baling press, simple in construction and effective in operation.

Referring to the drawings in which similar numerals indicate identical parts—

Figure 1 illustrates the application of my device to a baling press;

Figure 2 is an enlarged view of my invention showing the parts as set for operation with part of the bell broken away;

Figure 3 is a front elevation of Figure 2 with part of the bell broken away; and,

Figures 4, 5, 6 and 7 illustrate the various positions assumed by the tripping lever in operation.

The part of a baling press shown, to illustrate the application of my invention, is part of a baling chamber 1, of a well known type and constructed of angle steel bars 2, and flat bars 3, and having sides sufficiently open to accommodate the operation of tying the bale. Part of a finished bale 4 is shown and also part of a bale 5 in process of being formed, and separating them is the division block 6 provided with the usual grooves 7 through which the binding wire is fed.

My device comprises a support 8 having upper and lower horizontally disposed parts *a* and *b* spaced apart to form a horizontal slot 9 to receive the horizontal flange of the angle frame bar 2 and the flat bar 3 resting thereon. A bolt 10 secures the support rigidly in place. Extending upwardly from the support, and integral therewith, is an arm 11 the upper end of which is bent, as at 12, to form a seat for a bell 13 rigidly secured on the seat by a bolt 14 and a nut on the end of the bolt. A similar arm 16 extends upwardly from the support parallel with the arm 11 and of lesser length, and between the arms 11 and 16 a clapper 17 is pivotally supported on a bolt 18 which passes through both arms and the clapper and is secured by a nut 19.

A bolt 20 extends from the closed end of the slot 9 through a suitable opening in a boss 21

integral with the support 8, and on this bolt a lever 22 is pivotally mounted, intermediate its ends, and held thereon by a nut 23. The lever is bent below its pivot and from the bend extends downwardly parallel with the side of the press. Pivotally mounted on a bolt 24 in the upper end of the lever 22 is a swinging dog 25 having its upper end beveled downwardly toward the clapper 17 and in constant contact therewith. The dog 25 is elongated below its pivot into a narrow part 26 which is in normal contact with the nut 23 on the bolt 20. A coiled spring 27 has one end attached to the end of the bolt 20 and the opposite end attached to an end of the clapper 17. The striking end of the clapper 17 projects slightly beyond the bell 13, as shown in Figure 3, and between that end of the clapper and the pivot thereof is a bracket 28 riveted to the side of the clapper. A bolt 30 is adjustably held in a threaded aperture 31 in the support 8 and a boss 32 thereon and is held in any adjustment by a jam nut 33. A coiled spring 34 on the bolt 30 exerts its expansive force between the head of the bolt and a horizontal part 35 of the bracket 28 through which the bolt loosely extends.

Baling presses are provided with a device for retarding the progress of a completed bale on its way to the end of the press where it is finally ejected. This is necessary to preserve the compactness of the bale, so that the binding wire 36 can be placed, and also to insure a similar firmness of construction in the following bale being formed. Such retarding devices are of various types well known in the art but which I have not illustrated. As the bale emerges from the press the action of the retarding device thereon is consequently gradually lessened and the bale expands slowly longitudinally and takes up the slack in the wire with which the bale has been bound, as shown in dotted lines in Figure 1.

The lower part of the lever 22 is close to the bale so that the upper wire 36, as it is placed, encloses the lower part of the lever, as shown in Figure 1, and is tight enough to swing the lever in the direction of movement of the bale. As the lever swings on its pivot 20 the dog 25 operates against the adjacent end of the clapper 17.

per 17 and rocks the latter on its pivot 18 on the arms 11 and 16 on the support 8. The clapper rides up on the beveled end of the dog 25 and against the expansion of the spring 27 until the clapper has been rocked to its limit, the lever 22 and the dog and clapper then being in the position as shown in Figure 5. Further movement of the lever disengages the dog and the clapper, so that the latter, by contraction of the spring 27 is instantly rocked on its pivot 18 causing the opposite end of the clapper to strike the bell 13 with sufficient force to ring and so warn the operator of the press that sufficient material has been fed into the baling chamber to form a bale as 5.

It will be noted that the action of the spring 27 is contractile, and the action of the spring 34 is expansive, so that the action of both springs is to hold the clapper 17 substantially horizontal and free from contact with the bell 13 until it is actuated by operation of the lever 22 and the dog 25. When the clapper 17 is rocked by swinging motion of the lever the spring 27 forcibly expands by the rise of that end of the lever to which it is attached, consequently its contractile power is materially increased, at the same time the normal expansive power of the spring 34 is very much decreased, it therefore follows that with the instant release of the clapper from the dog, the former, by the sudden contraction of the spring 27 snaps back with sufficient force to cause its free end to strike the bell, then by the combined action of both springs the clapper is restored to its normal inoperative position.

After the dog 25 and clapper are disengaged the parts are as shown in Figure 6, the lever however is still being operated upon by the movement of the bale 4, the upper wire 36, holding the lever and actuating it, has been drawn taut. Dotted lines, in Figure 1, of the end of the lever indicate the limit of its movement by the bale. At this point the lever is free again and as it is loose on its pivot gravity swings it toward its normal position. As shown in Figure 6 the dog 25 has passed the clapper 17 and the latter is again in readiness for actuation; the dog however is on the side of the clapper opposite from its operative position, and its return to normal position to actuate the clapper is accomplished by the lever swinging a sufficient distance to cause the dog to rock on its pivot on the lever so as to pass the clapper, as shown in Figure 7, after which movement the lever and the dog return to the normal operative position shown in Figures 1 to 4 inclusive.

What I claim is—

1. In an alarm device for baling presses adapted to be mounted on a press, the combination of a support, a bell on the support, a clapper pivotally mounted intermediate its ends on the support, a lever pivotally mount-

ed intermediate its ends on the support and swingable by longitudinal movement of a bale, a dog pivotally supported intermediate its ends on the lever and operating to rock the clapper when the lever is swung a predetermined distance and to instantly release the clapper by continued swing of the lever whereby the clapper is caused to ring the bell.

2. In an alarm device for baling presses adapted to be mounted on a press, the combination of a support, a bell on the support, a clapper pivotally mounted intermediate its length on the support beneath the bell and extending transversely of the bell, a lever pivotally mounted intermediate its ends on the support and swingable by longitudinal movement of a bale, a dog pivotally supported on the lever above the pivot of the latter and having its upper end inclined and in contact with the clapper, said inclined end adapted to rock the clapper as the lever is swung a predetermined distance and to instantly release the clapper by continued swing of the lever whereby the clapper operates to ring the bell.

3. In an alarm device for baling presses adapted to be mounted on a press, the combination of a support, a bell on the support, a horizontally disposed clapper located beneath the bell transversely thereof and pivotally mounted intermediate its ends on the support, a lever pivotally mounted intermediate its ends on the support and adapted to be swung by longitudinal movement of a bale, a dog pivotally mounted intermediate its ends on the upper end of the lever and having its end inclined transversely of the clapper and normally in operative contact with the underside thereof, said inclined end adapted to rock the clapper as the lever is swung a predetermined distance and to pass by and suddenly release said clapper by continued swing of the lever whereby the clapper operates to ring the bell.

4. In an alarm device for baling presses adapted to be mounted on a press, the combination of a support, a bell on the support, a horizontally disposed clapper located beneath the bell transversely thereof and pivotally mounted intermediate its ends on the support, a lever pivotally mounted intermediate its ends on the support and adapted to be swung by a longitudinal movement of a bale, a coiled spring secured to the lever pivot extending upwardly and attached to the adjacent end of the clapper, a bracket on the clapper adjacent the striking end thereof, a bolt extending freely through an orifice in said bracket and secured to the support, a coiled spring on the bolt between the head thereof and the bracket, a dog pivotally mounted intermediate its ends on the upper end of the lever and normally in contact with the clapper, said dog operating to rock said clapper.

by swinging movement of the lever and to suddenly release the clapper when the lever has swung a predetermined distance whereby said springs operate to cause the clapper to 5 strike the bell and to resume its normal inert position.

5. In an alarm device for baling presses adapted to be mounted on a press, the combination of a support, a bell on the support, a clapper pivotally mounted on the support, a lever pivotally mounted on the support and operative by longitudinal movement of a bale to swing a predetermined distance and to swing back by gravity to its normal inoperative 10 position, a dog pivotally mounted on the lever and normally in contact with the clapper and actuated by movement of the lever to rock the clapper, said dog suddenly releasable from the clapper by continued movement of the lever whereby the dog rocks 15 to ring the bell, and means to restore said dog to its normal inoperating position.

6. In an alarm device for baling presses, the combination of a support having horizontally disposed parts spaced apart and adapted to be clamped on a press, parallel arms extending upwardly therefrom, a bell mounted on the upper termination of one of said arms, a clapper extending transversely beneath the bell and pivotally mounted intermediate its length on said arms and between them and normally out of contact with the bell, a lever pivotally mounted on the support, a dog pivotally mounted intermediate 30 its length on the lever and normally in contact with the clapper, said dog operative by a swinging movement of the lever to actuate the clapper to ring the bell, a coiled spring attached to the support and to the clapper 35 at one side of the pivot thereof, a bolt fastened to the support and extending above the opposite side of the clapper, and a coiled spring on the bolt between the free end thereof and the clapper.

40 7. In an alarm device for baling presses, the combination of a support having horizontally disposed parts spaced apart and adapted to be secured to a press, parallel arms extending upwardly therefrom, one of said 45 arms being longer than the other, a bell mounted on the longer arm, a clapper extending transversely beneath the bell and pivotally mounted intermediate its length on said arms and between them and normally out of 50 contact with the bell, a lever pivotally mounted on the support and extending above its pivot, a dog pivotally mounted intermediate its ends on the upper end of the lever and 55 normally in operative contact with the clapper, said dog adapted to be operated by a swinging of the lever to actuate the clapper, a bracket secured on one end of the clapper, an opening in said bracket, a bolt fastened to 60 the support and extending through said open-

ing, a nut on the free end of the bolt, a coiled spring on the bolt between said nut and bracket, and a coiled spring attached to the pivot of said lever and to the clapper.

In witness whereof, I hereunto subscribe 70 my name this 7th day of October, 1930.

FRANK D. JONES.
